PRESS FOR HEAT SEALING SHEET AND LIKE MULTIPLE PART OBJECTS

Dietrich G. Rempel, Akron, Ohio, assignor to Rempel Manufacturing, Inc., Akron, Ohio, a corporation of Ohio

Application May 28, 1953, Serial No. 358,043

11 Claims. (Cl. 154—1)

This invention relates to a press in which pressure, usually accompanied by heat, is employed to form uniting seams or joints between parts of fabricated articles. The invention also includes a novel structure of platen or work engaging part for such a press.

Many articles formed of sheet fabric and like materials are assembled from separate sheets or parts by seams initially formed by pressure and usually heat. Thus, air mattresses for military or camping use are formed from superimposed sheets of rubber impregnated fabric joined together along seams adjacent the sheet edges, and are usually provided with partitions dividing them into parallel tubular ridges by strips of similar fabric uniting the sheets along spaced substantially parallel lines. The economical assembly of such articles requires a press that simultaneously applies equal pressure, usually accompanied by heat, to both the edge seams and the seams joining the partitions to the upper and lower sheets of the article.

It is an object of the present invention to provide an improved press and press platen structure capable of applying substantially equal pressure to a plurality of seams between sheets or other substantially flat parts despite irregularities in seam thickness and irregular warping of press platens, bases or supports due to the heating of these parts incident to seam formation or due to other causes. Other objects of the invention will be pointed out or will become apparent from the following description of a preferred embodiment thereof.

In describing the invention in detail, reference will be made to the accompanying drawing, in which a press and press platen structure embodying the invention has been illustrated.

In the drawing:

Fig. 1 is a plan view of a press embodying the invention;

Fig. 2 is a front elevation of the press shown in Fig. 1;

Fig. 3 is an end elevation taken along the line 3—3 of Fig. 2;

Fig. 4 is a plan view of an air mattress which may be assembled on the disclosed embodiment of the improved press after being completed and inflated;

Fig. 5 is an enlarged sectional view of the mattress taken along the line 5—5 of Fig. 4;

Fig. 6 is a sectional view, on an enlarged scale, taken along the line 6—6 of Fig. 2;

Fig. 7 is an enlarged sectional view illustrating the detailed structure of the press;

Fig. 8 is a sectional view on an enlarged scale taken along the line 8—8 of Fig. 1;

Fig. 9 is an elevation on an enlarged scale of the latching mechanism employed in the disclosed embodiment of the press, showing the press parts closed and latched; and

Fig. 10 is an elevation similar to Fig. 9 showing the press parts unlatched.

Referring to the drawings, the press chosen to illustrate a typical embodiment of the invention includes generally a fixed substantially horizontal lower bed 11

2

supported by suitable legs 12 and an upper movable bed 13 hingedly secured to the lower bed adjacent the rear edge by suitable means, such as the hinges 14 (Figs. 1, 2 and 3). Each of the beds 11 and 13 is of box-like reinforced construction, including a substantially flat bed plate facing the press area and transversely and longitudinally extending reinforcing ribs, such as the ribs 15 shown in Fig. 1. A counterweight 16 carried between rearwardly extending arms 17 secured to or formed integral with the upper movable bed 13 permits easy lifting of the upper bed and normally holds it in an open position. Handles 18 are secured to the front face of the upper bed 13 to facilitate manual movement thereof between closed and open positions.

15 Suitable means are provided for releasably securing the upper bed 13 in its closed substantially horizontal position. In the disclosed embodiment, this means takes the form of a plurality of short latch rods 19, respectively secured at spaced points to and longitudinally movable 20 to latching and unlatching positions by a rod 20 extending along the front of the fixed lower bed 11 and slidably carried in openings through brackets 21 secured to and extending from the bed front. When the latch rods are moved to the right, as shown in Figs. 1, 2 and 9, they 25 pass through aligned openings in the brackets 21 and in cooperating brackets 22 fixed to the front face of the upper movable bed 13, and so releasably secure the beds in parallel adjacent relation when the upper bed is closed. Movement of the rod 20 to the left withdraws the latch 30 rods 19 from the bracket openings and so releases the connection to permit opening of the upper bed 13, as shown in Fig. 10. A handle 23 pivotally supported by a bracket 24 and connected by a link 25 to the rod 20 is employed to move the latch mechanism between open and closed 35 positions.

The platens or work engaging parts of the illustrated embodiment of the invention are particularly designed for pressing articles, such as air mattress parts, along seams at which the parts are to be joined. The upper platen 40 includes a metal plate 26 suitably secured to the flat lower face of the upper bed 13 with a layer of heat insulating material, such as asbestos 27, therebetween (Fig. 6). A plurality of downwardly protruding hollow seam pressing channels 28 are welded or otherwise suitably secured to 45 the under surface of the plate 26, and these channels terminate in narrow pressing ridges 29 which engage the work. Electrical heating elements 30 are disposed within the hollow channels 28 to heat the work engaging ridges 29. The arrangement of the channels 28 conforms to the pattern of seams to be formed, and in the disclosed embodiment includes a continuous edge channel 28' running adjacent the periphery of the platen in the form of the outline of the mattress to be formed and longitudinal parallel partition securing channels 28'' running lengthwise of the platen within the confines of the edge channel 28' (Fig. 1).

The lower platen is similarly constructed with a flexible metal plate 31 which, in a preferred embodiment, may comprise a sheet steel about $\frac{3}{16}$ of an inch in thickness 50 carrying upstanding hollow seam pressing channels 32 and 32'' terminating in upwardly presented narrow pressing ridges 33' and 33''. Electrical heating elements 34 are located in the hollow channels 32' and 32''. The heating elements 30 and 34 may be energized from a suitable 55 source through wire connections illustrated at 44, 45 and 52 in Fig. 3, and a switch 46 may be provided in this energizing circuit.

In accordance with the invention, the pressure for squeezing the work engaging surfaces of the platens is applied by the inflation of an air bag disposed between a flexible platen plate and the adjacent bed of the press. In the illustrated embodiment, the air bag 35 is a sub-

stantially flat relatively thin bag of natural or artificial rubber, or other suitable flexible air-tight material, disposed on the flat upper surface of the fixed lower press bed 11 and extending substantially throughout the width and length of the bed. A flexible layer 36 of heat insulating material, such as asbestos, is disposed between the upper face of the air bag and the plate 31 to avoid harmful heat deterioration of the air bag. The corners of the air bag preferably fall short of the corners of the bed 31 to permit the passage of securing bolts 37 between the bed 11 and the plate 13. These bolts 37, located adjacent the corners of the plate, as shown in Fig. 1, pass loosely through openings in the plate and threadedly engage the bed 11. The heads of the bolts 37 are spaced from the upper surface of the plate 31, so that the bolts permit limited floating movement of the plate 31 as the air bag 35 expands and collapses.

The air bag 35 is inflated and deflated through a suitable connection, here shown as a nipple 38, passing through the face of the lower bed 11. The nipple 38 has an enlarged head 39 which is clamped against the inner surface of the air bag 31 about an opening therein by a nut 40 threaded on the outer end of the nipple. The air hose 41 is employed to selectively connect the nipple 38 and the interior of the air bag 35 to a source of compressed air or to a vent under control of a manually operable valve 42, as illustrated in Fig. 3.

With the described arrangement, an article such as an air mattress may be readily assembled and such an operation will be briefly described. Two layers 47 and 48 of sheet material, such as textile fabric impregnated and, if desired, coated with natural or artificial rubber and having the desired shape, are superimposed with a series of lengthwise folded partition strips 49 of the same material arranged therebetween, as illustrated in Fig. 6. Strips 50 of paper or other liner material are preferably disposed between the juxtaposed surfaces of the folded strips 49 to prevent adherence between these faces. Powdered adhesive preventing material, such as zinc stearate, may be introduced between the areas of the sheet material layers 47 and 48 between the edge seams and the partitions, as illustrated at 51. The thus assembled parts are then placed in the opened press with the edge seam areas resting on the edge pressing ridges 33' and the ends of the folded partition strips 49 aligned with the pressing ridges 33". The upper press bed 13 is then lowered and latched to the lower bed 11 with the air bag 35 deflated. After latching of the press, the air bag 35 is inflated with air under substantial superatmospheric pressure. The heating elements 30 and 34 are desirably energized during the entire operation. The inflation of the air bag 35 presses the lower work engaging members against the assembled mattress parts and firmly squeezes them against the upper work engaging members, thereby forming heat and pressure sealed seams around the edges of the sheet material layers 47 and 48 and between each of the ends of each folded partition strip 49 and the adjacent inner surfaces of the adjacent sheet layers. After a considerable interval of such heat and pressure, the seams are sufficiently formed to permit removal of the assembled mattress from the press. This is done by venting the air bag 35 to atmosphere, unlatching and lifting the upper bed 13 and lifting out the assembled mattress. After suitable curing or vulcanizing, the mattress may be inflated for use, whereupon it takes the form illustrated in Figs. 4 and 5.

Due to the flexible floating application of pressure by the air bag through the work engaging members, the pressure applied along the several seams of the article is substantially uniform, and this despite differences in seam thickness or warping of the beds or other parts of the press due to temperature changes or gradients.

I claim:

1. A press comprising a substantially rigid bed; a relatively thin substantially flat inflatable bag overlying said bed and substantially coextensive therewith, a work en-

gaging member comprising a flexible sheet metal plate overlying said bag, a complementary work engaging member, means for mounting said bag and said complementary work engaging member for relative movement to admit a work piece between said complementary work engaging member and said plate, and means for releasably securing said complementary work engaging member to said bed adjacent said plate.

2. A press part comprising a substantially rigid bed, 10 a work engaging member comprising a flexible sheet metal plate overlying said bed, and an inflatable bag disposed between said bed and said plate and substantially coextensive therewith.

3. A press part comprising a substantially rigid bed, 15 a work engaging member comprising a flexible sheet metal plate overlying said bed, means for heating said work engaging member, an inflatable bag disposed between said bed and said plate and substantially coextensive therewith and a flexible layer of heating insulating material between said plate and said bag.

4. A press part comprising a substantially rigid bed, a work-engaging member comprising a flexible metal plate overlying said bed, an inflatable bag disposed between said bed and said plate and substantially coextensive therewith, and spaced work-engaging ridges carried by said flexible plate and extending from the side thereof remote from said inflatable bag.

5. A press comprising a substantially rigid bed, a work engaging member comprising a flexible sheet metal plate overlying said bed, means for heating said work engaging member, an inflatable bag disposed between said bed and said plate, a flexible layer of heating insulating material disposed between said bag and said plate, a complementary work engaging member hingedly secured to said base and movable between an open position remote from said plate and a closed position adjacent and substantially parallel thereto, and means for releasably securing said complementary work engaging member in such closed position.

6. A press comprising a substantially rigid bed, a work engaging member comprising a flexible sheet metal plate overlying said bed and having upstanding work engaging ridges on the upper surface thereof, means for heating said work engaging ridges, an inflatable bag disposed between said bed and said plate and substantially coextensive therewith, a flexible layer of heat insulating material disposed between said bag and said plate, a complementary substantially rigid work engaging member hingedly secured to said base and movable between an open position remote from said plate and a closed position adjacent and substantially parallel thereto, a plurality of work engaging ridges on the working surface of said complementary work engaging member substantially aligned with said work engaging ridges on said plate when said complementary work engaging member is in its closed position, means for heating said ridges of said complementary work engaging member and means for releasably securing said complementary work engaging member in its closed position.

7. A press comprising a substantially rigid bed, a relatively thin, substantially flat, inflatable bag overlying said bed and substantially coextensive therewith, a work engaging member comprising a flexible sheet metal plate overlying said bag, a complementary work engaging member, means for mounting said bag in said complementary work engaging member for relative movement to admit a work piece between said complementary work engaging member and said plate, means for releasably securing said complementary work engaging member to said bed adjacent said plate, said plate and said complementary work engaging member each being provided with work engaging ridges thereon, the ridges on said plate being in substantial alignment with the ridges on the complementary work engaging member when said comple-

mentary work engaging member is in its closed position, and means for heating said work engaging ridges.

8. A press comprising a substantially rigid bed, an inflatable bag overlying said bed, a flexible plate overlying said bag, a complementary work-engaging member, and means for moving said complementary work-engaging member relative to said flexible plate from a closed position where it is adjacent said flexible plate to an open position to admit a workpiece between, at least one of said complementary work-engaging member and said flexible 10 sheet having spaced work-engaging ridges.

9. A press as defined in claim 8 in which the work-engaging ridges are carried by the flexible plate.

10. A press as defined in claim 8 in which work-engaging ridges are carried both by the flexible plate 15 and the complementary work-engaging member, and the

work-engaging ridges on the complementary work-engaging member are substantially aligned with the work-engaging ridges on the flexible plate when said complementary work-engaging member is in its closed position.

11. A press as defined in claim 8 wherein the work-engaging member is mounted for pivotal movement relative to the bed and which includes means for securing the complementary work-engaging member to the bed.
